UNITED STATES PATENT OFFICE.

HORACE WYMAN, OF WORCESTER, MASSACHUSETTS, ASSIGNOR TO CROMPTON & KNOWLES
LOOM WORKS, A CORPORATION OF MASSACHUSETTS.

WEFT-REPLENISHING LOOM.

No. 876,418.

Specification of Letters Patent.

Patented Jan 14, 1908.

Application filed March 23, 1906. Serial No. 308,403.

To all whom it may concern:

Be it known that I, HORACE WYMAN, a citizen of the United States, residing at Worcester, in the county of Worcester and State of Massachusetts, have invented certain new and useful Improvements in Weft-Replenishing Looms, of which the following is a specification.

My invention relates to improvements in a weft replenishing loom of the class shown and described in U.S. Letters Patent, No. 808,966, in which there is a plurality of filling detector feelers, one for each shuttle; which feelers have a longitudinal movement and also a movement in the arc of a circle, and my invention particularly relates to improvements in the filling detector mechanism of the type shown and described in said patent, in which electro-magnets having movable cores or feelers are used.

It has been found in practice in the class of looms referred to, that it is desirable, after the feeler in line with the race-way of the lay has been moved backward by its engagement with the filling as the lay beats up, before the filling is practically exhausted, that it should be moved forward or positioned as the lay moves backward, preparatory to feeling for the filling on the next forward movement of the lay, and also that any one of the feelers, or all of the feelers, should be moved forward from their rear position, and positively maintained in their forward operative position, preparatory to indicating practical exhaustion of filling.

The object of my invention is to improve upon the construction of the filling detector or feeler mechanism of the type shown in said Patent, No. 808,966, and more particularly to provide means for moving forward each magnetized core or feeler, after it has been moved backwardly, and for positively maintaining each feeler in its forward normal position, for a predetermined time preparatory to its indicating substantial exhaustion of filling.

My invention consists in certain novel features of construction of my improvements, as will be hereinafter fully described.

I have only shown in the drawings a detached portion of a loom, and a filling detector or feeler mechanism of the type shown in said Patent, No. 808,966, with my improvements combined therewith, and adapted to be used on a two box, and a four box loom.

Some of the parts shown in the drawings and connected with and forming a part of the filling detecting mechanism, are of the same construction and operation as shown in U. S. Letters Patent, No. 805,109.

Referring to the drawings:—Figure 1 is a plan view of a filling detecting mechanism for a two box loom, embodying my improvements, looking in the direction of arrow *a*, Fig. 2. Fig. 2 is a rear view of the parts shown in Fig. 1, looking in the direction of arrow *b*, same figure. Fig. 3 is a section, on line 3, 3, Fig. 1, looking in the direction of arrow *c*, same figure. Fig. 4 is an end view of the parts shown in Fig. 2, looking in the direction of arrow *d*, same figure, and also shows two shuttles in cross section, with bobbins therein, and by broken lines a different position of one shuttle and bobbin, and of a filling detector, and of the positioning device. Fig. 5 shows the operating lever for the feelers, shown in Fig. 2, detached. Fig. 6 corresponds to Fig. 4, but shows a filling detecting mechanism for four shuttle boxes. Fig. 7 is a section, on line 7, 7, Fig. 6, looking in the direction of arrow *e*, same figure. Fig. 8 is a section, on line 8, 8, Fig. 6, looking in the direction of arrow *f*, same figure, and, Fig. 9 shows the stationary arm and the operating lever for the feelers shown in Fig. 7, detached.

In the accompanying drawings, Figs. 1 to 5 inclusive show the filling detecting mechanism of the type referred to for a loom with two shifting shuttle boxes, with my improvements combined therewith, and I will first describe the same.

1 is the upper part of a loom side or frame at the front of the loom, 2 is the breast beam, 3 is a bracket or stand bolted to the loom frame, and supporting at its outer end a stand 4, at the upper end of which are suitable bearings 4' for a shaft 4", on which is mounted the hub 6' of the filling detector or feeler carrying frame 6, which has a pivotal motion in a vertical plane, through the rod 7 connected with the vertically moving shuttle box rod, not shown. The frame 6 has supported thereon at its inner end two electro-magnets, each having filling detectors or feelers 8, one for each box or cell of the two shifting shuttle boxes, not shown, and for each shuttle 9 having therein a bobbin 9'.

The feelers 8 correspond to the feelers shown and described in said Patent, No. 808,966, and each consists of a balanced

magnetic body or pin, free to have a longitudinal movement within the center of a coil of wire 10, through which an electric current is adapted to pass, in this instance by means of wires 11 and 12, contact plates 6", spring blades 11' and 12', and wires 11" and 12" leading to opposite poles of any suitable source of electric energy, and forming a solenoid, or electro-magnet, all as fully described in said Patent No. 808,966.

The feelers 8 are preferably spirally grooved longitudinally on their external surfaces, to form channels or recesses in which any particles of dust or dirt may collect to leave the peripheral surface of said feelers smooth and even.

In connection with the filling detectors or feelers 8 is used a detector arm 13, having a hub 13' centrally pivoted on a stud 14. The upper end of said arm 13 extends in the path of movement of the feelers 8, and is adapted to be moved back of the same. A spiral spring 15 is supported on the stud 14, and is secured at one end on said stud, and engages with its other end the upper part of the detecting arm 13, and acts to move it back of the feeler 8 which is in line with the race-way of the lay, when said feeler is moved forwardly on practical-exhaustion of filling.

The detecting arm 13 has a downwardly extending arm which is pivotally connected with a rod 16, which preferably extends transversely through the loom to the opposite or weft replenishing end thereof; and is connected with the transferrer mechanism, not shown, of the weft replenishing mechanism.

A longitudinally moving rod 17 is guided in a stand 18, extending out from the bracket 3, and its inner end is adapted to engage the detecting arm 13 below its pivotal support, as shown in Fig. 2. The opposite end of the longitudinally moving rod 17 is attached to one arm of an angle lever 19, pivotally mounted on a stud 19'; the other arm of the angle lever 19 is attached to a vertically moving rod 20, which has a regular intermittent movement communicated thereto from some driven part of the loom, and causes the movement of the angle lever 19, and the longitudinal movement of the rod 17, to cause it to engage the detecting arm 13 below its pivotal support, and to positively move the upper end of said arm away from the feelers 8 at regular intervals, and also to be moved away from said detecting arm 13, as shown in Fig. 2, to allow the spring 15 to act to move the detecting arm 13 back of the feeler 8 which is in line with the race-way.

All of the above mentioned parts may be of substantially the same construction and operation as similar parts shown and described in Patents, No. 808,966, and No. 805,109, above referred to.

I will now describe my improvements combined with the parts above described for a

two box loom, and which consist, as above stated, of mechanism, independent of the feelers, for moving forward or positioning the feelers, after they have been moved back by engagement with the filling carrier on the forward movement of the lay, and for positively maintaining each feeler in its forward normal position, preparatory to indicating substantial exhaustion of filling.

I preferably provide an operating lever 27 of the shape shown in Fig. 5, which has two hubs 21 and 21', which are loosely mounted on a stud 22, and a stud 22', respectively, on the stand 4. An arm 23 extends downwardly and outwardly from the hub 21', and has an inclined or cam shaped engaging surface 23' thereon, extending in the path of and adapted to be engaged, in this instance, by a set screw 24 on a collar 25 fast on the longitudinally moving rod 17, see Fig. 1. The collar 25 may be adjusted on the rod 17 and secured thereon by said screw 24.

The operating lever 27 extends up from the hubs 21 and 21' in a vertical plane, and is located directly back of and in line with the rear ends of the longitudinally moving feelers 8. The engaging face of the lever 27 is made curved to conform to the arc of the vertical movement of the feelers 8, see Figs. 3 and 4. A non-magnetized plate 27' is preferably secured on the engaging face of the lever 27, at a point in line with the feeler 8 for the shuttle which is on a line with the race. The non-magnetized plate 27' acts to leave the feeler 8 free to be drawn forward by engagement with the ring on the bobbin, in the well known way.

In connection with the lever 27, I preferably use two flat or leaf springs 28, and 29, secured at one end on the stand 4, and engaging at their free ends projections 30 and 31 on the lever 27, one spring, as 28, acting on the lever 27, above its pivot point, and the other spring, as 29, below its pivot point, as shown in Fig. 3. The spring 29 acts to move forward the lever 27, and yieldingly hold a projection 27^a thereon against a stop 27^b, see Fig. 2, and in engagement with the outer ends of the feelers 8. The spring 28 acts as a balance spring, and both springs 28 and 29 are preferably very light, so that the lever 27 is easily moved backward from contact with a feeler 8, when said feeler is moved backward by the engagement of a full bobbin, as shown by dotted lines in Fig. 4.

The operation of the lever 27 will be readily understood. At every outward movement of the longitudinal rod 17 it engages the detecting arm 13 and moves it away from and out of the path of the feelers 8, and at the same time the set screw 24 on the collar 25 moves into the recessed part on the engaging surface 23' of the arm 23 of the lever 27, (see Fig. 1,) so that the lever 27 is free to be moved backward, against the action of the spring 29

29, by the engagement of a feeler 8 therewith, which feeler may be moved outwardly by contact with its bobbin on the forward stroke of the lay, in the usual way. As the 5 lay returns, or moves backward, the spring 29 will act to move forward the lever 27, and with it the feelers 8, to their forward normal position, until the lever 27 engages its stop 27^a. The movement of the rod 17 in its opposite direction at the proper time will release 10 the detecting arm 13 in the usual way and will at the same time move the set screw 24 back of the inclined end of the engaging surface 23' of the arm 23, as shown by broken 15 lines in Fig. 1, to hold said arm 23, and positively maintain the lever 27 in its forward position, in engagement with the feelers 8, to positively position and hold the feelers 8 in their forward operative position. At the 20 proper time, the movement of the rod 17 in an outward direction, will release the arm 23 from the set screw 24 and leave the lever 27 free to be moved back by the outward movement of a feeler 8, as above described.

25 I will now describe my improvements applied to a four box loom, and shown in Figs. 6, 7, 8, and 9 of the drawings. In said figures, the same figures of reference are used as in the preceding figures, for similar parts. 30 The filling detecting frame 6^a carries four electro-magnets, each having a feeler 8, one for each of the four shuttles 9. The vertically moving rod 7 is in this instance pivotally connected with one end of a lever 32, 35 which has a hub 32' at its other end pivotally mounted on a stud 33' on an extension 4^a on the stand 4. A link or connector 34 is pivotally attached at one end to a pin 32'' on the lever 32, and at its other end to a pin 35' on an arm 35 on the arc shaped portion 6^a of the feeler supporting frame 6^a. My mechanism for engaging and moving the feelers 8 into their forward position, and positively maintaining them in their normal 40 position, consists in this instance of a stationary engaging arm 36, which has on its lower end an offset attaching lug 36' secured to the stand 4 by two screws 37, see Figs. 6 and 8, and at its upper end the curved 45 engaging surface 36'' extending in the path of and adapted to engage the feelers 8, when they are above the plane of the race-way of the lay. Below the engaging part 36'' the arm 36 is offset, as shown in Fig. 9, to admit 50 of the engaging part 38' of the rocking operating lever 38, corresponding to the operating lever 27 above described. The engaging part 38' of the operating lever 38 extends in the path of and is adapted 55 to engage the feeler 8 which is in line with the race-way of the lay. The operating lever 38 has two hub portions 38'' which are loosely mounted on studs 39 on the stand 4^a, and a downwardly and outwardly extending engaging arm 38' of inclined or

cam shape on its inner engaging surface, as shown in Fig. 8, and extending in the path of and adapted to be engaged by the set screw 24 on the collar 25, adjustably secured by a set screw on the longitudinally moving 70 rod 17. Extending below the engaging part 38' of the operating lever 38, and in the same vertical plane therewith, and with the stationary engaging surface 36'' of the stationary arm 36, is a slotted plate 40, formed in this instance 75 by a bar 40' secured to the stationary arm 36 by a screw 41. The slotted plate 40 is adapted to receive the headed outer end of a feeler 8, as the feelers 8 are moved down with their supporting frame, to hold said 80 feelers, and prevent them from dropping out of the coils of wire 10. The two leaf springs 28^a and 29^a, which are preferably used, are attached at their inner ends on the stand 4^a, and engage with their free ends the 85 operating lever 38; one spring, as 28^a, acting on the lever 38 above its pivot point, and the other spring, as 29^a, below its pivot point, as shown in Fig. 6. The spring 29^a corresponds to the spring 29, above described, and acts to move forward the lever 38, and yieldingly hold it against a stop 38^a, and in engagement with the outer end of the feeler 8, in line with the race-way of the lay. The spring 28^a corresponds to the spring 28, 95 above described, and acts in the same way.

The operation of my mechanism for a four shuttle box loom, to move the feelers 8 forward, and to positively maintain the same in their normal position, will be readily understood by those skilled in the art. As the feelers 8 are raised and lowered with the supporting frame 6^a, to extend in a plane above or below the race-way of the lay, the feeler or feelers above the plane of the race-way of the lay, will engage with the stationary engaging surface 36'' of the stationary arm 36, and be moved forward and positively maintained in their normal position, and the feeler or feelers below the plane of the race-way of the lay, will be engaged by the slotted plate 41, and be maintained in their proper position, while the feeler in line with the race-way of the lay will be engaged by the engaging end 38'' on the operating 105 lever 38, and moved forward and positively maintained in its forward normal position by the set screw 24 extending back of the inclined end of the arm 38'' of the lever 38 to hold said lever in its forward position, 110 the same as above described in connection with the lever 27. The movement of the set screw 24 into the recessed part of the engaging arm 38'' will release the lever 38 and allow it to be moved back against 115 the action of the spring 29^a by the engagement of a feeler 8 therewith, as above described in connection with the lever 27.

It will be understood that the details of construction of my improvements may be 120

varied if desired, and they may be adapted to be used in connection with shifting shuttle boxes having two or more cells for shuttles.

Having thus described my invention, what I claim as new and desire to secure by Letters Patent is:—

1. In a weft replenishing loom, the combination with an electro-magnet carried on a frame and having a movable core for a feeler, of means for engaging and positioning said core, and positively maintaining it in its operative position for a predetermined time.
2. In a weft replenishing loom, the combination with a plurality of electro-magnets carried on a frame, and each magnet having a movable core for a feeler, of means for engaging and positioning each movable core or feeler, and positively maintaining it in its operative position for a predetermined time.
3. In a weft replenishing loom, the combination with an electro-magnet carried on a frame and having a movable core for a feeler, said feeler adapted to enter a shuttle box on the forward beat of the lay and engage the filling carrier therein, of means for moving said filling detector into its forward operative position on the backward movement of the lay, and positively maintaining it in its operative position for a predetermined time.

4. In a weft replenishing loom, the combination with a plurality of electro-magnets carried on a frame and having a pivotal movement in a vertical plane, and each magnet having a movable core for a feeler, of means for moving a movable core into its forward operative position, preparatory to its entering a shuttle and engaging the filling carrier thereon on the forward beat of the lay, and positively maintaining it in its operative position for a predetermined time.

5. In a loom, a movable filling detector feeler to engage the filling in the shuttle, and means to normally position the feeler preparatory to its contacting with the filling, and positively maintaining it in its operative position for a predetermined time.

6. In a loom, a plurality of movable filling detector feelers to engage the filling in the shuttles, each feeler having grooves or channels therein, and means to normally position a feeler preparatory to its contacting with the filling, and positively maintaining it in its operative position for a predetermined time.

HORACE WYMAN.
